JOHN WILKINSON, OF SYRACUSE, NEW YORK, ASSIGNOR TO H. H. FRANKLIN
MANUFACTURING COMPANY, OF SYRACUSE, NEW YORK, A CORPORATION OF
NEW YORK.

FORCE-FEED LUBRICATOR.

1,300,798.

Specification of Letters Patent. Patented Apr. 15, 1919.

Application filed June 22, 1916. Serial No. 105,138.

To all whom it may concern:

Be it known that I, JOHN WILKINSON, a citizen of the United States, and a resident of Syracuse, in the county of Onondaga and State of New York, have invented a certain new and useful Force-Feed Lubricator, of which the following is a specification.

This invention has for its object a force feed lubricator, particularly adapted for motor vehicles in which each outlet passage, leading to the various parts of the vehicle to be lubricated, receives an individual impulse during each cycle of movement of the lubricator.

In describing this invention, reference is had to the accompanying drawings, in which like characters designate corresponding parts in all the views.

Figure 1 is a plan view of the base of the pump with the container removed.

Fig. 2 is a sectional view on the plane of line 2—2, Fig. 1, the container being shown.

Fig. 3 is an inner face view, partly broken away, of the pump.

Fig. 4 is a detail view of the base plate and the plate thereon, the plate being partly broken away.

Fig. 5 is an enlarged sectional view through one of the compression chambers of the pump illustrating the means for regulating the pressure of the pump.

This lubricator comprises, generally, a body formed with a series of outlet passages which have inlet ports arranged in a series, and a movable distributor having a delivery passage movable successively into alignment with the ports of said series and communicating at all times with the compression chamber of the pump.

I have here shown this invention as embodied in a gear pump, that is, a pump the movable parts of which comprise intermeshing gears.

1 designates the base of the lubricator, which base is provided with a series of grooves 2, the inner ends of which are arranged in a circular series.

3 is a plate mounted on the base 1 and covering said grooves 2, the plate being formed with perforations 4 near the margins thereof which register with the outer ends of said grooves and with a series of perforations 5 at the inner ends thereof which register with the inner ends of the grooves. The perforations 4 constitute out-

let ports and the perforations 5 a circular series of inlet ports, for the outlet passages formed by said grooves 2 and the overlying plate 3.

6 is a container, or the sides and top of the lubricator body, the container being mounted above the plate 3 and having passages 7 which communicate with the outlet ports 4. The container 6 is secured to the base plate 2 and the plate 3 in any suitable manner, and preferably the margin of the plate 3 extends under the edge of the container.

The pump includes a casing located in the body and movable parts in the casing. 8 designates the pump casing which casing is mounted on the plate 3. The movable parts are here shown as intermeshing gears 9, 10 located in the casing contiguous to the plate 3, one of the gears, as the gear 10, serving as a distributor and being arranged with its axis concentric with the axis of the circular series of ports 5, and being provided with a delivery passage 11 arranged to come into alignment successively with the ports of the series 5.

The gears 9, 10 are mounted respectively upon shafts 12, 13 journaled respectively in bearings in the casing 8 and the base 1. The pump casing 8 is secured in position in any suitable manner, as by screws 14 extending through the margin thereof and extending through the plate 3 and into the plate 1.

The pump is also provided with an annular compression chamber 15 arranged concentric with the axis of the gear 10 and, as here shown, it is formed in said gear 10 and one end of the delivery passage 11 opens thereinto. This annular compression chamber opens into another compression chamber 16 formed in the casing 8 and provided with means therein for regulating the pressure of the pump.

The pressure regulating means, as here shown, includes a valve 17 operable to close or open more or less, a by-pass 18 which communicates with the compression chamber 16 at one end and with the interior of the container 6 at its other end, so that if desired a portion of the oil may be forced back into the container.

The pump casing is provided with a suitable inlet 19 opening into the container 6 and located on the opposite side of the point

at which the gears 9, 10 mesh to that on which the compression chamber 16 is located.

5 The gear 9 is actuated by a shaft suitably coupled to the upper end of the shaft 12 which extends through the casing 8 into the container 6, connection being made with this shaft 12 through a passage 21 in the top of the container 6. The body of the lubricator is usually supported on the crank casting of an engine or any other suitable part.

10 In operation, the oil flows from the container 6 through the inlet 19 into the interior of the pump casing 8 when it is pumped 15 into the compression chamber 16 and flows therefrom into the compression chamber 15 of the distributing gear, from which it passes through the passage 11 through the outlet passages, and through the ports 5.

15 20 This lubricator is particularly advantageous in that owing to the fact that each outlet passage receives an individual impulse, each part to be lubricated will always receive the proper amount of oil and obstruction of the passages is prevented.

25 What I claim is:—

30 1. A force feed lubricator having a circular series of outlet ports and a pump including a rotary distributor arranged concentric with the axis of the series of the ports and formed with a transverse delivery passage extending in the direction of the axis of the distributor and opening through opposite side faces of the distributor, the delivery passage being arranged to register successively with said outlet ports, substantially as and for the purpose described.

35 40 45 2. A force feed lubricator comprising a body formed with a series of circular outlet ports, and a pump including a casing and intermeshing gears located in the casing, one of said gears being arranged with its axis coincident with the axis of the series of outlet ports and having a delivery passage therethrough eccentric to said axis and movable successively into registration with the outlet ports, substantially as and for the purpose set forth.

50 55 60 65 3. A force feed lubricator comprising a body formed with a circular series of outlet ports, and a pump including a casing, and movable elements in the casing, said elements including intermeshing gears, one of the gears serving as a distributor and being arranged with its axis coincident with the axis of said series of outlet ports and formed with a delivery passage arranged to come successively into alignment with the outlet ports, the pump also including an annular compression chamber arranged concentric with the axis of said distributor and into which the delivery passage opens, substantially as and for the purpose described.

65 70 75 80 4. A force feed lubricator comprising a body having a circular series of outlet ports,

and a pump including a rotary distributor arranged concentric with the axis of said series and formed with a delivery passage arranged to register successively with said outlet ports, and means for adjusting the pressure through the delivery passage, substantially as and for the purpose specified.

80 85 90 95 5. A force feed lubricator comprising a body formed with a circular series of outlet ports, and a pump including a casing, movable elements including intermeshing gears, one of the gears serving as a distributor and being arranged with its axis coincident with the axis of said series of outlet ports and formed with a delivery passage arranged to come successively into alignment with the outlet ports, the pump also including an annular compression chamber arranged concentric with said distributor and into which the delivery passage opens, and means for adjusting the pressure in said annular passage, substantially as and for the purpose set forth.

100 105 110 115 6. A force feed lubricator comprising a body formed with a circular series of outlet ports, and a pump including a casing formed with a compression chamber, movable elements in the casing including a rotary distributor arranged with its axis coincident with the axis of said series of outlet ports, and with a delivery passage arranged to come successively into alignment with said ports, the pump also including an annular compression chamber communicating with the former compression chamber and arranged concentric with the axis of the distributor and into which the delivery passage opens, and means located in the first-mentioned compression chamber for regulating the pressure therein, substantially as and for the purpose described.

120 125 130 135 7. A force feed lubricator comprising a body formed with a circular series of outlet ports, and a pump including a casing, movable elements in the casing, said elements including intermeshing gears, one of the gears serving as a distributor and being arranged with its axis coincident with the axis of said series of outlet ports and formed with a delivery passage arranged to come successively into alignment with the outlet ports, the pump also including an annular compression chamber arranged concentric with said distributor and into which the delivery passage opens, and means in the former compression chamber for adjusting the pressure therein, substantially as and for the purpose specified.

8. A force feed lubricator comprising a body including a base plate formed with a series of radially extending grooves in one face thereof, the inner ends of which grooves are arranged in a circular series, a plate overlying the grooves and formed with per-

forations in alinement with the inner and outer ends of the grooves, those at the inner end constituting a circular series of inlet ports for the grooves, and those at the outer end, outlet ports, a container mounted above the base and the plate and having passages communicating with the inlet ports, and a pump including a casing mounted within the container, and movable parts including intermeshing gear wheels located in the casing, one of the gear wheels being arranged with its axis coincident with the axis of the circular series of ports and formed with a de-

livery passage arranged to come into alinement successively with the ports of said circular series, the pump being also formed with a compression chamber including an annular portion arranged concentric with the axis of said distributor gear into which one end of the delivery passage opens, substantially as and for the purpose specified. 15 20

In testimony whereof, I have hereunto signed my name at Syracuse, in the county of Onondaga, and State of New York, this 6th day of June, 1916.

JOHN WILKINSON.
